UNITED STATES PATENT OFFICE.

LOUIS B. HASBROUCK, OF ELMIRA, NEW YORK, ASSIGNOR TO ECLIPSE TEXTILE DEVICES, INC., OF ELMIRA, NEW YORK, A CORPORATION OF NEW YORK.

DYEING APPARATUS.

Application filed January 12, 1928. Serial No. 246,131.

This invention relates to dyeing apparatus, and aims to provide means for dyeing different parts of an absorbent mass with different colors.

5 A particular object of the invention is to provide a machine for spotting yarn while the yarn is wound in a mass, and to produce bands of different colors around such a mass, each band extending from the outer to the inner 10 surface of the mass.

The invention may best be understood by a detailed description of a practical machine embodying it. Such a machine is shown in the accompanying drawings, in which:—

15 Fig. 1 is a plan view with the base plate partly broken away;

Fig. 2 is an enlarged longitudinal section taken on the line 2—2 of Fig. 1;

20 Fig. 3 is a horizontal section taken on the line 3—3 of Fig. 4; and

Fig. 4 is a transverse section on the line 4—4 of Fig. 1.

The machine shown has a base plate B which may be supported at about the height 25 of an ordinary work bench by means not shown in the drawings. On the base plate B is mounted a pumping device P and a work holder W. In the operation of the machine, the pumping device draws different colored 30 dyes from a plurality of separate reservoirs, T^a, T^b, T^c, T^d, and forces limited quantities of the different colored dyes into separate portions of a cone of yarn on the work holder W.

35 The pumping device P includes a cylinder block P¹ containing a plurality of vertical bores P^{2a}, P^{2b}, P^{2c}, P^{2d}, all of which are closed at their lower ends except for small drain openings P⁴, communicating with valve-controlled drain pipes P⁵ extending through an 40 opening in the plate B. The pistons P^{6a}, P^{6b}, P^{6c}, P^{6d} of the pumping device are driven from a shaft P⁷ mounted on the lower side of the plate B and driven through a pumping press clutch so that it may be given a single 45 revolution when desired by the operator. On the shaft P⁷ is a crank P⁸ connected by means of a connecting rod P⁹ to the free end of a lever P¹⁰ fulcrumed on a bracket, P¹¹ mounted on the cylinder block P¹. The lever P¹⁰ is 50 connected by a link P¹² to a slide P¹³ mounted on a vertical rod P¹⁴, which is slidable in two bearings P¹⁵ formed on the cylinder block P¹. The pistons are connected with the slide P¹³ so as to be reciprocated thereby.

The length of the stroke of the slide P¹³ 55 may be varied by attaching the upper end of the connecting rod P⁹ in any one of the number of holes P¹⁶ in the lever P¹⁰. The lengths of the strokes of the individual pistons may also be adjusted. In the form illustrated, the 60 pistons P^{6a}, and P^{6b} are directly connected to the slide P¹³, so that their strokes are the same length as that of the slide, while the pistons P^{6c}, P^{6d} are connected to the slide in such a way as to allow for a regulatable amount of 65 lost motion. For this purpose, the piston rods P¹⁸ of the pistons P^{6c}, P^{6d} are slidable in holes in the slide P¹³, and are provided with fixed collars P¹⁹ below the slide, and adjustable collars P^{20a} and P^{20d} above the slide. It is apparent from this arrangement that the stroke 70 of the piston P^{6c} is less than the stroke of the slide P¹³ by the amount by which the distance between its collars P¹⁹ and P^{20a} exceeds the thickness of the slide. Thus with the adjustment shown in Fig. 4, the piston P^{6c} has a stroke shorter than that of the pistons P^{6a} and P^{6b}, which move with the slide, and longer 75 than that of the piston P^{6d}.

The inlet openings P^{21a}, P^{21b}, P^{21c}, P^{21d} of the cylinders are connected by pipes P²² to the separate dye reservoirs T^a, T^b, T^c, T^d which may be located below the plate B. Each of the pipes P²² contains a check valve 80 P²³.

An outlet opening P²⁴, located near the bottom of each cylinder, communicates directly with one of a plurality of injectors J^a, J^b, J^c, J^d attached to one side of the cylinder block. 85

Each injector comprises a double nozzle J¹ and two needles J² fixed in the discharge openings of the nozzle. The nozzle J¹ has a body J³ on the rear end of which is a threaded stem J⁴ which is screwed into a nipple J⁵ attached to the cylinder block P¹ over one of the outlet openings P²⁴. The stem J⁴ contains a nozzle bore J⁶ which is the intake opening of the nozzle J¹. In an enlarged bore in the front portion of the body J³ is located a chuck J¹⁰ containing two longitudinal bores J¹¹ whose outer ends form the discharge openings in the nozzle J¹. To permit compression of the inner portions of the bores J¹¹ in order to grip the needles therein, the rear portion of the chuck contains a diametrical slit J¹² at the inner end of which is a transverse bore J¹³ extending across the two bores J¹¹, and a transverse slit J¹⁴. The chuck J¹⁰ is retained 90 95 100 105

in the body J^3 by a nut J^{15} which is screwed on the front end of the body and engages the chuck J^{10} so as to force the conical inner end J^{16} of the chuck against a conical seat in the body. The chuck J^{10} has at its outer end a projection J^{17} which is thrust into the mass to be dyed when the mass is brought into operative relation with the injector. On the outer end of the nut J^{15} is an annular projection J^{18} 10 lying some distance behind the outer end of the projection J^{17} .

Each of the needles J^2 has a solid rear end portion J^{19} which is clamped in the inner portions upon the bores J^{11} by screwing the nut J^{15} inward. As the shaft of the needle is of 15 uniform diameter, it may be gripped at any point by the chuck, so that the distance which it projects beyond the end of the projection J^{17} may be varied. The needle has a pointed 20 front end whose apex J^{20} is its axis. The needle contains an open longitudinal groove J^{21} which extends from the portion of the needle crossing the bore J^{13} as nearly as possible to its apex J^{20} .

25 The work holder W comprises a carriage W^1 carrying a standard W^2 in which a shaft W^3 is rotatably mounted. On one end of the shaft W^3 is a cone holder W^4 adapted to carry a cone of yarn C by engagement with the 30 card-board core C^1 on which such a cone is ordinarily wound.

The carriage W^1 is reciprocatable in directions parallel to the needles J^2 , $J^{2'}$, and adjustable transversely to the needles. The 35 carriage is slidably mounted on rods W^8 fixed on a frame W^9 which is mounted on a transverse rod W^{10} adjustably secured in standards W^{11} projecting up from the plate B . A shaft W^{12} rotatably mounted in similar standards 40 W^{13} assists in supporting the frame W^9 and provides for reciprocating the carriage W^1 on the rods W^8 . For this purpose, the shaft W^{12} is provided with a gear W^{14} meshing with a rack W^{15} on the bottom of the carriage. A 45 handle W^{16} is provided for turning the shaft W^{12} .

The shaft W^3 and the cone holder W^4 are rotated through a small arc at each reciprocation of the carriage by means of a ratchet 50 wheel W^{17} fixed on the shaft W^3 , and a pawl W^{18} carried by a bar W^{19} fixed to the outer ends of the rods W^8 . Further rotation of the shaft W^3 may be obtained by turning a hand wheel W^{20} also fixed on the shaft W^3 .

55 In the use of the machine, the tanks T^a , T^b , T^c , T^d are filled with liquid dyes of different colors. After a cone has been placed on the cone holder W^4 , the carriage is moved towards the injectors by turning the handle W^{16} until 60 its movement is arrested by an adjustable stop W^{21} . This causes the needles of each injector to penetrate the yarn. The slide P^{13} is then given a single reciprocatory movement which forces the different colored dyes 65 previously drawn into the bores of the cylinder

block through the separate injectors into the portions of the cone immediately surrounding the needles of each injector. The carriage W^1 is then returned to the position shown in Fig. 1, the pawl and ratchet W^{17} , W^{18} causing a slight rotation of the cone C during the latter part of this movement. The operation is then repeated until four separate zones C^{2a} , C^{2b} , C^{2c} , C^{2d} , each extending completely around the cone and extending from its outer to its inner surface, have been saturated with the four differently colored dyes. 75

Substantially uniform saturation of the 80 yarn in each of the four zones and uniform width of the four zones is secured by forcing a greater quantity of liquid into the zones which are of larger diameter and consequently of larger volume. The quantity of dye injected into each zone of the cone is measured by the volume of the portion of one of the bores below its piston when the piston is at the upper end of its stroke. From the connections between the pistons and the slide P^{13} already described, and the setting of the 85 collars P^{20c} and P^{20d} of the pistons P^{6c} , P^{6d} , it is apparent that the smallest quantity of dye is injected into the zone C^{2d} nearest the smaller end of the cone. A larger quantity is injected into the zone C^{2c} , while still larger 95 quantities are injected into the zones C^{2a} and C^{2b} . This arrangement has proved satisfactory in practice, but it is apparent that, if desired, the machine may be arranged to inject different quantities of it into the zones 100 C^{2a} and C^{2b} by connecting the piston P^{6b} to the slide P^{13} in the same way as that in which the pistons P^{6c} and P^{6d} are connected thereto.

Certain parts of the machine illustrated herein form part of the subject matter of my co-pending application, filed April 8, 1926, Serial No. 100,486, and my co-pending applications filed March 14, 1927, Serial Nos. 175,081 and 175,082, and are therefore not claimed herein. 105

What I claim is:

1. A dyeing machine, comprising the combination with a support for a mass of yarn, of a plurality of reservoirs containing different colored dyes, means for withdrawing from each reservoir a measured quantity of dye insufficient in amount to dye the entire mass, and means for simultaneously causing such measured quantities of the different colored dyes to penetrate through different parts of 115 the mass on the holder. 120

2. A dyeing machine, comprising the combination with a support for a mass of yarn, of a plurality of reservoirs containing different colored dyes, and means for causing dye from each reservoir to penetrate simultaneously into different parts of the mass on the support. 125

3. A dyeing machine, comprising the combination with a holder for a mass of yarn, of a plurality of dye reservoirs, a plurality of 130

pumps, one connected to each of said reservoirs, a plurality of injectors directed towards different parts of the mass on the holder and one connected to each of said pumps, and common driving means for causing simultaneous operation of the pumps.

4. In dyeing apparatus, the combination with a support for a cone of yarn, of means for measuring out two different quantities of liquid, means for causing the smaller measured quantity of liquid to penetrate into a zone of the cone on the support, and means for simultaneously causing the larger measured quantity of liquid to penetrate into a zone of the cone located nearer its larger end.

5. In dyeing apparatus, the combination of a support for a cone of yarn, two injectors directed toward different zones of the cone on the support, a pump connected with each injector, a common operating means for said pumps, and means for varying the length of

the stroke of the piston of one pump with respect to that of the other pump.

6. In a dyeing machine, the combination of a cylinder block containing a plurality of bores, a reciprocating slide at one end of said block, a piston in one of said bores fixedly connected to said slide, pistons in the other bores slidably connected with said slide, and collars on the last mentioned pistons above and below the slide.

7. In a dyeing machine, the combination of a cylinder block containing a plurality of bores, a reciprocating slide at one end of said block, pistons in the bores slidably connected with said slide, collars on the pistons above and below the slide, and means for adjustably varying the distance between the collars of each piston.

In testimony whereof I have hereunto set my hand.

LOUIS B. HASBROUCK.
